INFRA-RED WARMER FOR CELLOPHANE WRAPPED FOOD

Joseph A. Hanna, 1210 Hills Bldg., Utica, N.Y.

Filed July 18, 1963, Ser. No. 75,870

Term of patent 7 years

(Cl. D81—10)

FIGURE 1 is a front elevational view of an infra-red warmer for cellophane wrapped food, showing my new design;

FIGURE 2 is a sectional view taken on the line 2—2 of FIGURE 1;

FIGURE 3 is a sectional view taken on the line 3—3 of FIGURE 1; and

FIGURE 4 is a sectional view taken on the line 4—4 of FIGURE 1.

The top is plain and the undisclosed side is substantially the same in appearance as the side shown.

I claim:

The ornamental design for an infra-red warmer for

cellophane wrapped food, substantially as shown and described.
